M. ABRAMOWITZ.
 EDGE TURNING ATTACHMENT FOR SEWING MACHINES.
 APPLICATION FILED JAN. 8, 1912.
 1,085,958. Patented Feb. 3, 1914.

UNITED STATES PATENT OFFICE.

MOTEL ABRAMOWITZ, OF MONTREAL, QUEBEC, CANADA.

EDGE-TURNING ATTACHMENT FOR SEWING-MACHINES.

1,085,958.

Specification of Letters Patent.

Patented Feb. 3, 1914.

Application filed January 8, 1912. Serial No. 670,014.

To all whom it may concern:

Be it known that I, MOTEL ABRAMOWITZ, of the city of Montreal, Province of Quebec, Canada, have invented certain new and useful Improvements in Edge-Turning Attachments for Sewing-Machines; and I do hereby declare that the following is a full, clear, and exact description of the same.

The object of my invention is to provide a new and improved device for turning in the stitched edges of the layers of material used in making up a garment whereby the right side of the folded over edges may be sewn by the machine without the necessity of first basting down such edges.

The principal object of the invention is to provide guides for folding over the stitched layers upon themselves and directing the so formed folded edges to the machine needle and a device for retaining such edges in their proper folded position in the approach to the needle.

For full comprehension, however, of my invention reference must be had to the accompanying drawings forming a part of this specification, in which similar reference characters indicate the same parts and wherein:

Figure 1 is a perspective view with parts broken away of my improved hemming attachment applied to a sewing machine; Fig. 2 is a plan view thereof with a portion broken away; Fig. 3 is an enlarged vertical section taken on line 3-3 Fig. 2; Fig. 4 is a similar view of normal size taken on line 4-4 Fig. 2; Fig. 5 is a detail vertical section on line 5-5 Fig. 1; Fig. 6 is a face view of the abutment with some of the parts in transverse section; and Fig. 7 is a vertical section of the completed hem.

In the drawing *a* indicates the head of a sewing machine, *b* the needle and *c* the table portion of the machine.

The hemming attachment comprises an abutment *d* presenting a guide plate *e* disposed at an angle thereto, a holding member *f* between which and the abutment the folded edges of the garment are held, a guiding member *g* adapted to direct such edges to the holding member and a cover plate *h* for retaining the proper folded position of the fabric as it moves from the holding member to the needle *b*.

The abutment is preferably in the form of a vertically disposed or edgewise mounted wall upon the machine and extending from

a point adjacent to and at one side of the needle, outwardly therefrom a suitable distance, being held in such position by an extension *i* at one side which is pivoted as at 60 15 to a slotted plate *j* secured upon the table *c* by a thumb screw 16, the slot extending at right angles to the abutment *d* so as to permit of a sidewise adjustment of the latter relatively to the needle to vary the distance of the stitching from the folded edge of the garment. At the opposite side of the abutment, that is at the side exposed to the needle, the guide plate *e* is presented being at right angles to the abutment and extending from the outer end of the latter inwardly and downwardly to a point a suitable distance from the needle and above the table *c*, the outer edge of the plate being longitudinally tapered from the outer end 70 thereof to its inner end where it merges into the vertical surface of the abutment. The pivot 15 permits the abutment to be swung out of its normal position when desired.

The holding device *f* is suitably supported adjacent to the inner end of the guide plate and a sufficient distance above the table *c* to allow the fabric to pass beneath and is formed with a forked end at such point by means of which the fold of the hem is formed, as will be presently described.

In order to form the forked end of the member *f* and at the same time facilitate the passage of the folded fabric between it and the abutment I have utilized a flanged roller, the inner end of the plate *e* being centrally located with relation to the flanges *k* of the roller so that when the folded edge of the garment is moved inwardly along the guide *e* (being directed toward the needle by the abutment) the stitched edge 12 will assume a position between the flanges *k* with the main portions *r* and *s* over and under the roller. To further facilitate the accurate engagement of the edge of the garment with the roller I have provided the guide *g* which is located in front of the roller and comprises a member presenting a mouth *l* with flared lips *m* located one above and one below the guide *e*. The mouth extends from the outer end of the member *g* inwardly toward the abutment to a point adjacent to the roller, the space between the rear wall of the mouth and the abutment gradually decreasing from the outer to the inner end of the former, thus

the edge of the garment may be readily brought into engagement with the guide and by such means easily engaged with the roller.

5 As seen by the drawings I prefer to space the roller and the inner end of the guide *g* just a sufficient distance from the abutment to permit a single thickness of fabric to pass between, so, to provide for different thickness I have made these members adjustable 10 relatively to the abutment and as this adjustment is carried out the same way in both cases I will only describe it in connection with the roller.

15 The roller is rotatably supported by the member *f* which is carried by a shank *o* held in a suitably supported carrier *p*. Between the carrier and the shank there is a frictional connection formed by means of a 20 member *q* hinged to the cut-away end *u* of the shank and a spring *v* located between the member *q* and the cut-away portion. When the shank *o* is in its normal position shown by the drawings any end thrust to 25 which it may be subjected is taken up by an interior stop *w* presented by the carrier *p*.

To adjust the position of the roller relatively to the abutment for the purpose above pointed out, the member *q* is pressed 30 against the influence of the spring *v* thus permitting the shank to be moved longitudinally toward the abutment, movement away from the abutment being permitted to a limited extent by pressing the hinged member *q* down so that the corner *p'* thereof will 35 pass beneath the stop *w*.

I have illustrated the shank *o* as being formed in two portions, one of which is located in a socket presented by the other 40 and removably secured therein by a pin *x*.

As the folded edge of the garment passes from the roller to the needle it is held in proper position and the folds are brought into close contact with each other in readiness to be sewn, through the medium of the 45 top cover plate *h* which extends over the roller and guide *g*, in close relation to the abutment *d* and is inclined from the roller downwardly toward the needle so that the 50 edge is gradually pressed into tight folded position before being sewn. The cover plate is carried by the presser foot 10 by means of a vertical extension 17 and a set screw 18 while a slot 19 permits of a longitudinal adjustment to maintain its position relatively 55 to the abutment when the latter is adjusted.

Operation: When a garment is to be hemmed the edges are first sewn, and here- 60 tofore the top and bottom portions *r* and *s* were basted in their folded positions before being again sewed, but in the present invention the garment, after the first line of stitching has been sewn, is, without being 65 basted, directly applied to the attachment

with the plate *e* between the portions *r* and *s* which are respectively turned over and under the stitched portion 12. As the folded edge is fed toward the needle and the guide *g* is reached the stitched portion 12 enters 70 the mouth *l* while the portions *r* and *s* pass over and under the lips *m* and in this position it is directed by the inwardly extending mouth *l* and tapered plate *e* to the roller, 75 engaging therewith and having the portion 12 between the flanges *k* and the portions *r* and *s* respectively between the cover *h* and top of the roller and between the table *c* and bottom of the roller. The folded edge is then guided between the table *c* and down- 80 wardly inclined cover plate *h* to the needle where it is sewn as at 14 thus completing the hem.

I claim:

1. In a sewing machine attachment for 85 folding the edges of a fabric, the combination with a needle,—of an abutment mounted upon the sewing machine independent of the presser foot, a guide plate mounted edge-wise at an angle upon the abutment, tapered 90 toward the latter and terminating at a point spaced from the needle and a member located adjacent to the tapered edge of the guide plate and at the outer side thereof with relation to the abutment and adapted 95 to hold the fabric against the guide plate.

2. The combination with a sewing machine and its needle, of an attachment for 100 folding the edges of a fabric, including an upright abutment having mounted thereon an angularly disposed guide plate tapered 105 toward the abutment and terminating at a point spaced from the needle, a forked device located adjacent to the termination of the guide plate, such device holding the 110 fabric against the abutment, and a cover plate located above the holding device and extending downwardly therefrom to a point at the side of the needle.

3. The combination with a sewing machine, its needle and the table portion thereof, of an attachment for folding the edges of a fabric, including a vertical abutment secured to the table with its inner end adjacent to the needle, a downwardly inclined 115 guide plate mounted on the abutment at right angles thereto and longitudinally tapered toward the said abutment, terminating at a point spaced from the needle, a 120 suitably supported flanged roller located adjacent to the termination of the guide plate, such roller holding the fabric against the abutment, a suitably supported guide situated in front of the roller and presenting a mouth partially inclosing the said guide 125 plate, and a cover plate extending from the needle upwardly over the said roller and guide.

4. The combination with a sewing machine, its needle and the table portion there- 130

of, of an attachment for folding the edges of a fabric, including a vertical abutment secured to the table with its inner end adjacent to the needle, a downwardly inclined 5 guide plate mounted on the abutment at right angles thereto and longitudinally tapered toward the said abutment, terminating at a point spaced from the needle, a carrier, a shank having at one end a frictional connection with the carrier, a flanged 10 roller supported at the opposite end of the shank at a point adjacent to the termination of the guide plate, such roller holding the fabric against the abutment, a second 15 shank situated in front of the first men-

tioned shank and having at one end a frictional connection with the said carrier, a guide supported at the opposite end of the second shank and presenting a mouth partially inclosing the said guide plate, and a 20 cover plate extending from the needle upwardly over the said roller and guide.

In testimony whereof, I have signed my name to this specification, in the presence of two subscribing witnesses.

MOTEL ABRAMOWITZ.
